UNITED STATES PATENT OFFICE.

JOSEPH B. STRAUSS, OF CHICAGO, ILLINOIS.

CONCRETE CAR.

1,299,411.

Specification of Letters Patent.

Patented Apr. 1, 1919.

Application filed July 29, 1918. Serial No. 247,168.

To all whom it may concern:

Be it known that I, JOSEPH B. STRAUSS, a citizen of the United States, residing at Chicago, in the county of Cook and State 5 of Illinois, have invented a certain new and useful Improvement in Concrete Cars, of which the following is a specification.

This invention relates to a concrete car and has for its object to provide a new and 10 improved car of this description. The invention has among other objects to provide a concrete car reinforced by metal in such a manner as to take care of the severe strains and properly transmit them into the concrete, thereby producing a strong and durable structure capable of withstanding shocks and strains due to railway service. The invention is illustrated in the accompanying drawings wherein—

20 Figure 1 is a side elevation of one form of car embodying the invention.

Fig. 2 is a sectional view taken on line 2—2 of Fig. 1.

Fig. 3 is an enlarged view taken on line 25 3—3 of Fig. 1 with the metal reinforcement in full lines and the concrete portion of the car body in dotted line.

Fig. 4 is a vertical section through one 30 wall of the car and a portion of the bottom showing a modified construction.

Fig. 5 is a sectional view taken on line 5—5 of Fig. 6.

Fig. 6 is a sectional view taken on line 6—6 of Fig. 5.

35 Fig. 7 is a plan view with parts omitted of a portion of the bottom metal reinforcing frame work.

Fig. 8 is an enlarged sectional view with parts omitted taken on line 8—8 of Fig. 1.

40 Fig. 9 is an enlarged sectional view with parts omitted taken on line 9—9 of Fig. 1.

Fig. 10 is an enlarged sectional view with parts omitted taken on line 10—10 of Fig. 1.

Fig. 11 is a view showing in elevation one 45 of the reinforcement engaging projections shown in plan in Fig. 7.

Fig. 12 is a sectional view through a portion of the bottom and wall of a car showing a modified construction.

50 Like numerals refer to like parts throughout the several figures.

Referring now to Fig. 1 and associated figures: I have shown a concrete car having a concrete body, a concrete bottom and concrete side walls and end walls, there being suitable metal reinforcement in said bottom

and walls. Extending longitudinally of the car, at the bottom thereof, is a metal member 1, which is in the form of a beam or girder. The draw bars 2 are connected to 60 this longitudinal member.

At the bottom of the car body, preferably opposite the floor, I provide a metal frame 3 which extends all the way around the body forming a metal rectangle. In each end of 65 the car at the point where it is connected with the truck I provide a transverse metal member 4, which is preferably made up of two sections, the inner ends thereof being connected to the longitudinal member 1. 70 (See Fig. 7).

I also prefer to provide angle members 5, which are connected at one end with the longitudinal member 1 and at the other end with the transverse member 4. This construction may be formed in any desired manner, but as herein shown I provide plates 6, by means of which the members 5 are connected with the members 4 and 7, by means of which members 5 are connected with the 75 member 1. A metal piece 8 connects the two sections of the transverse member 4 and extends across the top of the member 1. Reinforcing metal pieces 9 are embedded in the side wall 10 of the car and are connected 80 with plates 6 and transverse members 4. 85 (See Figs. 7 and 10).

I prefer to provide at the top of the car a metal frame 11 which extends along both sides and both ends and which forms a rectangular metal frame. The metal frames 3 and 11 are preferably connected together at the corners by the metal pieces 12, thus forming a complete box metal frame which forms the corners and the top portions of 90 the walls of the car. The reinforcing pieces 9 extend through the top member of the frame 11. (See Fig. 10).

Metal plates 13 are provided, said plates connecting the side members of the frame 3 100 with the ends of the transverse members 4. (See Fig. 11).

The trucks 13^a are connected with the metal members 1 and 4 in any desired manner and by the ordinary king pins 14.

105 The side walls 10 are provided at the point where the transverse metal member 4 is located with reinforced ribs 15. These walls are also provided at intervals with reinforced ribs 16 and the bottom is also provided with reinforced ribs 17, integral with the floor, the inner ends thereof abutting

longitudinal metal member 1. The floor and walls of the car are provided with reinforcing metal members which preferably interlock. One method of inserting these members is shown in Figs. 5 and 6. In these figures there are a series of floor reinforcing members 18, which floor members are bent up at the ends as shown in Fig. 5 and connect with the longitudinal wall reinforcing members 19. The walls are preferably also provided with the diagonal reinforcing members 20 and 21, which are connected with the metal frames 3 and 11. It will be noted that these diagonal members are placed more closely together at the points where the greater strains and stresses are located, that is, near the ends of the car where the car body is connected with the trucks.

The concrete ribs 17 at the bottom of the car are preferably provided with the inclined reinforcing members 22, which are in the form of a truss, the outer ends of which are connected with the plates 23. These plates are connected with the metal frame 3 and extend along the ends of the ribs 17. I prefer also to provide the metal corner pieces 24 at the bottom of these ribs.

The members 22 extend entirely across the car as illustrated in Fig. 2, preferably passing above longitudinal member 1, and are similarly connected at their opposite ends. I also prefer to provide these ribs with a similar reinforcing metal member 22^a, which extends below the member 1. I also prefer to provide metal reinforcing members 26 which connect the corner pieces 24 and the frames 3 and 11. Along the walls 10, at other places than where the ribs occur, I provide reinforcing metal pieces 27 (see Fig. 8), which connect the frames 3 and 11. The reinforcing pieces 9, 26 and 27 are preferably made adjustable as by means of nuts and screw threads, as shown in Figs. 8, 9 and 10.

The reinforcing members 27, for example, may be connected to the eyebolts 28 which pass through the frame 3 and are held in place by the nuts 29. These reinforcing members may be held to the top by means of the heads 30, or in any other desired manner.

At the ends of the car body I prefer to provide the reinforcing members 30 (see Fig. 3), which extend across the end and part way along the sides. I also prefer to provide the reinforcing members 31 which extend part way across the end and part way along the sides, as shown in Fig. 3. The members 30 and 31 are preferably in the same horizontal plane although this relation may be changed if desired.

I prefer to provide at the ends the inclined reinforcing members 32 which are connected with the floor and which extend along the sides in the inclined position, as

shown in Fig. 5, and which then extend across the ends through the ribs 33. (See Figs. 2 and 5).

The metal members 4 act as bolsters and I prefer to provide reinforcement engaging 70 projections 34 to be attached to said members 4 and also the central longitudinal member or sill 1. One of these reinforcement engaging projections is illustrated in Fig. 11 and may consist of angle pieces, one angle 75 of which is connected to the member with which the device is associated, the other angle projecting therefrom and being provided with one or more grooves 34^a to receive the central reinforcing member or members. 80 The longitudinal member 1 may be made in any desired manner and as herein shown is of box girder construction comprising two side members suitably connected together and provided with a space between them. I 85 prefer to provide at intervals between these members the connecting pieces 1^a. The draw bar at each end passes into this space and there are opposed inwardly projecting members 35 (see Fig. 7) between which the draw 90 bar passes.

In Fig. 4 I have shown a modified construction wherein the reinforcement consists of an expanded metal or woven metallic section 10^a. It will be seen that in this construction I provide a concrete car body having a concrete floor with metal reinforcement therein and metal members or frame pieces connected with the body, the floor reinforcement interlocking with the metal members. It will further be seen that the longitudinal metal member acts as a beam to carry part of the load of the body and that the side walls, which are integral with the concrete floor, have exposed top and bottom 105 metal members, the reinforcement in the side walls being connected therewith. The side walls act as girders to carry a portion of the load of the car body, the entire structure forming as it were a unitary car body. 110 The parts are also arranged to properly take care of the strain and stresses due to the draw bar pull both longitudinal and lateral and will also take care of the stresses and strains due to the connection of the body 115 with the trucks.

It will further be noted that the concrete ribs at the bottom of the car and the metal transverse members 4 have their inner ends abutting the central metal member. In Fig. 120 12 I have shown a modified construction wherein the longitudinal member 1 is provided at the top with the pieces 36, which are shown as Z bars and which are connected at the top by the plate 37. The floor abuts 125 these Z bars, as shown, and there are provided reinforcing members 38 which are connected at their inner ends with the Z bars or central longitudinal member, their outer ends being bent up into the walls as shown. 130

There are also the looped or truss reinforcing members 39, which extend all the way across and preferably pass above the central longitudinal member and through the 2 bars. There are also the reinforcing members 40, which connect with the opposite sides of the frame 3 and which extend entirely across the bottom. The members 38 are located at intervals all along the bottom 10 of the car while the members 39 and 40 are only at the points where the floor ribs or beams 17 are located. The members 38 may also be used in the construction shown in Figs. 1 and 8.

15 Fig. 9 shows a construction where the reinforcing members in the reinforced ribs 17 are arranged somewhat different from that shown in Fig. 2. In this construction member 22 is arranged as shown in Fig. 2 but 20 the other member 22^b instead of crossing the member 22 is attached to the parts 23 and 24 in the same horizontal plane.

I have described in detail a particular construction embodying my invention, but 25 it is of course evident that the parts may be varied in form, construction and arrangement without departing from the spirit of the invention as set forth in the claims hereto appended, and I therefore do not 30 limit myself to the particular construction shown.

I claim:

1. A concrete car comprising two frames, one frame consisting of a central longitudinal metal member, and transverse metal members connected thereto, the other frame being an exterior bounding frame, a connection between the two frames, a concrete floor and concrete walls integral therewith, the 40 bounding frame being on the exterior of the concrete.

2. A concrete car comprising two frames, one frame consisting of a central longitudinal metal member and transverse members 45 connected thereto, the other frame being an exterior bounding frame consisting of an upper section and a lower section connected together, a connection between said lower section and the first mentioned frame, a concrete floor and concrete walls integral therewith the bounding frame being on the exterior of the concrete walls.

3. A concrete car body comprising a concrete floor, metal reinforcement in said 55 floor, a longitudinal member underlying said floor and running the full length thereof in the center, transverse metal members connected thereto near the ends and means for interlocking the metal reinforcement in the 60 floor to the longitudinal and transverse members.

4. A concrete car comprising two frames, one frame consisting of a central longitudinal metal member and transverse metal 65 members connected thereto, the other frame

being an exterior bounding frame, a connection between the two frames, a concrete floor and concrete walls integral therewith, the bounding frame being on the exterior of the concrete, a series of reinforced ribs integral 70 with said concrete walls and reinforced ribs integral with said floor.

5. A concrete car body comprising a concrete floor, metal reinforcement therein, a longitudinal metal member under said floor 75 extending substantially its full length, transverse metal members connected to said longitudinal members, draw bars connected with said longitudinal members, the floor reinforcement interlocked with the said metal 80 members, the longitudinal metal member acting as a beam to carry part of the load of the body, side walls integral with the concrete floor, said side walls having exposed top and bottom metal members, metal reinforcement in said side walls and connected with said top and bottom members, the side walls acting as girders to carry a portion of the load of the car body, the whole forming 85 a unitary car body.

6. A concrete car body comprising a concrete floor, metal reinforcement therein, a longitudinal metal member under said floor extending substantially its full length, transverse metal members connected to said longitudinal members, draw bars connected with said longitudinal members, the floor reinforcement interlocked with the said metal member, side walls integral with the concrete floor, said side walls having exposed 90 top and bottom metal members, metal reinforcement in said side walls, connected with said top and bottom members, the side walls acting as girders to carry a portion of the load of the car body; flanges at the 95 top of said walls and ribs between said flanges and the floor, the whole forming a unitary car body.

7. A concrete car body comprising a concrete floor, metal reinforcement therein, floor beams integral with said floor, a longitudinal steel member under said floor extending substantially its full length, transverse metal members connected to said longitudinal members, draw bars connected with said longitudinal members, the floor reinforcement interlocked with the metal members, transverse metal members acting to distribute the draw bar pull into the floor, the longitudinal metal members acting as a beam 110 to carry part of the load of the body, side walls carrying the remainder of said load, said side walls integral with the concrete floor, said side walls having exposed top and bottom metal members, metal reinforcement in said side walls, connected with said top and bottom members, the side walls acting as girders and provided with flanges at the top, ribs between said flanges and the floor, said ribs located at the ends of the 115 120 125 130

- floor beams and connected thereto, the whole forming a unitary car body.
8. A concrete car body comprising a concrete floor, metal reinforcement embedded therein, metal members underlying said floor, comprising a longitudinal member the full length of the floor and transverse members near the ends thereof, members connecting the ends of the transverse members and the ends of the central longitudinal member, said concrete floor interlocked with said metal members.
9. A concrete car comprising a concrete floor, metal reinforcement therein, separate metal members underlying said floor, comprising a central longitudinal member and transverse members near their ends, the reinforcement in the floor interlocked with the metal members, reinforced concrete floor beams under the floor at intervals and integral therewith, said floor beams abutting the central metal member and connected thereto.
10. A concrete car comprising a concrete floor, metal reinforcement therein, separate metal members underlying said floor, comprising a central longitudinal member and transverse members near their ends, the reinforcement in the floor interlocked with the metal members, reinforced concrete floor beams under the floor at intervals integral therewith, said floor beams abutting the central metal member and connected thereto, walls integral with the floor and the floor beams, said walls provided with an upper flange and ribs integral with the walls between said flange and the floor.
11. A concrete car comprising a concrete floor, metal reinforcement therein, separate metal members underlying said floor, comprising a central longitudinal member, transverse members near their ends, the reinforcement in the floor interlocked with the metal members, reinforced concrete floor beams under the floor at intervals, integral therewith, said floor beams abutting the central metal member, side walls having their lower portions integral with the floor and the floor beams, a flange at the top of said side walls and ribs between said flange and the floor.
12. A concrete car comprising a concrete floor, metal reinforcement therein, separate metal members underlying said floor, comprising a central longitudinal member, transverse members connected thereto near their ends, the reinforcement in the floor interlocked with said metal members, reinforced concrete floor beams under the floor at intervals and integral therewith, said floor beams abutting the central metal member, walls having their lower portions integral with the floor and the floor beams, ribs integral with said walls and extending above the top of the wall so as to leave open spaces to be closed by non-integral side pieces.
13. A concrete car comprising a concrete floor, metal reinforcement therein, separate metal members underlying said floor, comprising a central longitudinal member, transverse members near their ends, the reinforcement in the floor interlocked with the metal members, reinforced concrete floor beams under the floor at intervals, integral therewith, said floor beams abutting the central metal member, walls having their lower portions integral with the floor and the floor beams, ribs integral with the walls, said ribs extending above the top of the walls so as to leave open spaces, non-integral side pieces for said open spaces, and a roof supported upon said extended ribs.
14. A concrete car body comprising a concrete floor, metal reinforcement embedded therein, metal members underlying said floor, comprising a longitudinal metal member extending substantially the full length of the floor and transverse metal members near their ends, members connecting the ends of the transverse members and the ends of the central longitudinal member, said concrete floor interlocked with said metal members, concrete walls and ends integral with the floor and with each other, reinforcement in said walls and ends interconnected with the floor, a mid-rib on the end walls parallel with the floor, inclined ribs on the side walls running from said mid-rib to the floor, and reinforcement in said inclined rib connecting the ends of said rib to the transverse metal member.
15. A concrete car comprising a concrete floor, metal reinforcement embedded therein, metal members underlying said floor, comprising a longitudinal metal member extending the full length of the floor and transverse members near the ends of the longitudinal members, said concrete floor interlocking with said longitudinal and transverse metal members.
16. A concrete car comprising a main frame comprising a central longitudinal metal member, transverse metal members connected thereto near the ends, a reinforced concrete car body superimposed upon said main frame, metal reinforcement in the car body, said metal reinforcement interlocking with the main frame to form a unitary whole and prevent separation under shock.
17. A concrete car comprising a main frame comprising a central longitudinal metal member, transverse metal members connected thereto near the ends, a reinforced concrete car body superimposed upon said main frame, means for interconnecting them to form a unitary whole, said car body comprising integral concrete walls and floors, transverse floor beams under the floor, longitudinal flanges on the walls, longitudinal mid-ribs on the walls, vertical ribs on

said walls, said floor beams flanges and ribs integral with said walls and reinforcement interconnecting all the parts.

18. A concrete car comprising a concrete floor and concrete walls integral therewith, a metal bounding frame on the exterior of said concrete consisting of an upper rectangular section and a lower rectangular section and exterior corner pieces connecting them together, and a reinforcing connection between said sections intermediate said corner pieces and embedded in the concrete.

19. A concrete car comprising a main frame, embracing a central metal sill and transverse metal bolsters connected thereto at the ends and comprising a car body mounted thereon, said car body having metal framework at the sides, said metal framework connected to the metal sills and bolsters, reinforced concrete floor and walls supported upon and contained between the sills, bolsters and metal frame, reinforcement in said floor and walls, said reinforcement interlocked with the metal sills, bolsters and metal frame.

20. A concrete car comprising a concrete floor and concrete walls integral therewith, a metal bounding frame on the exterior of said concrete consisting of an upper rectangular section and a lower rectangular section and exterior corner pieces in the form of angles connecting them together, and a

reinforcing connection between said sections intermediate said corner pieces and embedded in the concrete, the upper rectangular section of said bounding frame consisting of metal channel pieces extending across the top of the car walls and partway down the outer and inner faces thereof. 35

21. In a concrete car, a metal central longitudinal member, transverse metal pieces at the ends thereof, a metal frame at the outside limits of said central member and transverse members, reinforced concrete beams extending between said metal frame and said longitudinal member, a concrete floor supported on said frame and beams and abutting the central longitudinal member and connected thereto, and reinforced concrete side walls and ends integral with said concrete floor and concrete floor beams. 40 45

22. A concrete car, comprising a concrete body having walls and a floor, metal members connected with said floor, reinforcing metal pieces for said floor and reinforcement 55 engaging projections on said metal members which engage said reinforcing metal pieces.

In testimony whereof I affix my signature, in the presence of two witnesses, this 20th day of July, 1918.

JOSEPH B. STRAUSS.
